[57] CLAIM

The ornamental design for a travel pillow, as shown and described.

DESCRIPTION

FIG. 1 is a rear perspective view of a travel pillow in accordance with the invention;

FIG. 2 is a top view thereof with the top edge facing the rear side;

FIG. 3 is a front view thereof;

FIG. 4 is a right side view thereof; and,

FIG. 5 is a bottom view thereof.

That which is depicted in solid lines in the drawing represents the claimed invention and that which is depicted in broken lines, if any, in the drawing forms no part of the claimed invention.
